FIG. 1 is a perspective view of a water ride vehicle intake shown with a water ride vehicle as environment in broken lines;

FIG. 2 is a perspective view of a water ride vehicle intake; FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The broken lines shown in FIGS. 1-4 and 6-8 are for the purpose of illustrating portions of the water ride vehicle intake that form no part of the claimed design. The dot-dash lines shown in FIGS. 1-4 and 6-8 define the boundary of the claim which forms no part of the claimed design. The vehicle shown in broken lines in FIG. 1 represents the environment in which the claimed water ride vehicle intake resides and forms no part of the claimed design.
